UNITED STATES PATENT OFFICE.

GEORGE F. CONNORS, OF LEADVILLE, COLORADO.

RAZOR.

1,259,724.

Specification of Letters Patent. Patented Mar. 19, 1918.

Application filed April 20, 1917. Serial No. 163,373.

To all whom it may concern:

Be it known that I, GEORGE F. CONNORS, a citizen of the United States, and a resident of Leadville, in the county of Lake 5 and State of Colorado, have made certain new and useful Improvements in Razors, of which the following is a specification.

My invention is an improvement in razors and has for its object to provide a 10 razor wherein interchangeable blades may be used without departing from the construction of the non-safety type of razor.

In the drawings—

Figure 1 is a side view of the razor with 15 parts broken away, showing one type of blade.

Fig. 2 is a partial side view showing another type of blade.

Figs. 3 and 4 are sections on the lines 20 3—3 and 4—4 respectively, of Fig. 1, and

Figs. 5 and 6 are side views of other embodiments of blades.

In the present embodiment of the invention, a holder is provided of the non-safety 25 type, the said holder comprising a handle portion 1, said holder to be described later, which is pivoted to the handle as at 2, in a manner to permit the edge of the blade to be swung into the handle or into the position 30 of Fig. 1, as when used in shaving.

The holder comprises a substantially U shaped portion consisting of a body 3 and side walls 4, and a shank 5, which is pivoted to the handle. The holder is formed 35 by bending sheet metal into proper shape, the strip of sheet metal being doubled upon itself to form the holder. The body of the holder is beaded or cylindrical, as shown in Fig. 3, the side walls lying close to each 40 other when the razor is not in place, and at the shank the sides are U-shaped, as shown in Fig. 4.

The removable and reversible blades 6, 8 and 9, are alike in one respect, each having 45 a beaded back portion 10, the bead being preferably formed hollow by bending back the upper edge against the body portion, and adapted to be received in the bead 3 of the holder and held thereby at its upper 50 and lower portions, to prevent downward movement of the blade with respect to the holder. The blades are of such length with respect to the holder that the beads will extend practically the whole length of the

body 3 of the holder, and the side walls 4 55 of the holder are of a width to extend near the edge of the razor but to leave enough of the edge exposed to permit shaving, stropping and honing.

The improved razor is used in the same 60 manner as the old-fashioned or non-safety type, and when a blade becomes dull, it may be stropped or honed in the same manner as the old-fashioned razor. When the blade becomes too dull for use, it may be removed 65 and replaced by a new blade, the cut out portion 16 at the toe or front end facilitating these operations and preventing injury to the fingers by the sharp edge of the blade.

The blade 6, shown in Fig. 1, has its outer 70 corner rounded as indicated at 11, while the inner corner 12 is angular. The blade shown in Fig. 2 is the blade shown in Fig. 1 reversed, that is turned end for end, the rounded corner 11 being inward, while the 75 angular corner 12 is outward.

If desired, both corners of the cutting edge of the blade may be rounded as shown at 13 for the razor 8 in Fig. 5, or both corners may be angular, as shown at 14 for 80 the razor 9 in Fig. 6. The improved blades are thin like those used in the safety razor, but they are supported by the gripping action of the bead 3 and the width of the side walls of the holder in the same manner as 85 the non-safety type blades. It will be noticed that the blade is limited in its inward movement in the holder by inwardly bent portions 15 at the junction of the shank 90 with the holder.

I claim:

A razor of the character specified comprising a blade carrying member and a tang member made from an integral sheet of resilient material bent back upon itself to 95 form spaced apart side walls, the tang portion being of less width than the blade carrying member, said blade holding portion expanded at its bend into a cylindrical bead, said bead merging longitudinally into the 100 tang and having its side walls crimped inwardly in alignment with the merging point and of relatively great width, and a removable and reversible blade consisting of a web having one edge sharpened and its 105 opposite edge rolled back upon itself into a tubular bead, said bead being centered and held within the cylindrical bead of the blade

holder and contacted thereby at three points; the heel end of the blade abutting the crimps of the side walls and the point of merger of the blade holding bead and 5 tang, and the side walls of the blade holder embracing the blade over a greater portion of its width from toe to heel, and the toe

ends of the side walls having curved scallops to permit the fingers to insert the blade in the holder and remove same therefrom. 10
